UNITED STATES PATENT OFFICE.

FREDERICK L. OWEN, OF BOSTON, MASSACHUSETTS.

GARMENT-HANGER.

1,336,375.

Specification of Letters Patent.

Patented Apr. 6, 1920.

Application filed July 30, 1919. Serial No. 314,211.

To all whom it may concern:

Be it known that I, FREDERICK L. OWEN, a citizen of the United States, and a resident of Allston, Boston, in the county of 5 Suffolk and State of Massachusetts, have invented a new and Improved Garment-Hanger, of which the following is a full, clear, and exact description.

The present invention relates to new and 10 useful improvements in garment hangers, and it pertains more particularly to means for retaining the garments in place on the hangers.

In garment hangers as commonly constructed, great difficulty has been experienced in keeping the garments in proper position when hanging thereon, this being particularly true in the case of light-weight garments, such as ladies' blouses and the like, 15 and it is the primary object of the present invention to retain these garments in proper position on the hanger.

A further object of the present invention is to provide resilient means for this purpose, together with means for adjusting the tension of the resilient means for the purpose of permitting the device to be used with a multiplicity of garments placed on the same hanger.

30 With the above and other objects in view, reference is had to the accompanying drawings in which—

Figure 1 is a view in elevation of a garment hanger of the folding type provided 35 with the attachment constituting the present invention;

Fig. 2 is a top plan view thereof;

Fig. 3 is a view in elevation of the hanger in its folded form;

40 Fig. 4 is a view in elevation of a modified form of the invention.

Fig. 5 is a fragmentary view of a still further modified form of the invention.

Referring more particularly to the drawings, the hanger comprises two arms 5 and 6, which are pivoted together as at 7, the pivoting member of said arms comprising a right-angular extension of a supporting hook 8.

50 On the upper edge of each of the arms 5 and 6, is provided a resilient clasp 9, which is secured in position by means of screws or the like 10, and secured to the under edge

of each of the arms 5 and 6, as by screws 11, are resilient clasps 12, these clasps being 55 relatively smaller than the clasps 9. The outer end of each of the clasps 9 and 12 is curved, as at 13, to prevent tearing of the garments on the hanger and permit of their easy insert between the clasps and their respective arms.

Each of the resilient clasps 9 and 12 is provided with a suitable opening, which openings when the clasps are in their proper position on the arms of the hanger, are 65 adapted to align with each other, and passing through the openings in each of the clasps and an opening aligned therewith in each of the arms 5 and 6, are bolts 15, the lower end of each of which is threaded as 70 at 16. Having engagement with the threaded ends 16 of the bolts 15, are thumb nuts 17, which are adapted to engage the smaller resilient clasps, the head of each of the bolts 15 engaging its respective larger resilient 75 clasp 9.

By this construction it will be seen that as the nuts 17 are backed off the screw-threaded ends 16 of the bolts 15, the resilient clasps 9 and 12 are free to be sprung out of 80 engagement with their respective arm 5 or 6, in order that the garments may be inserted thereunder.

After the desired number of garments have been placed on the hanger, the nuts 85 17 are moved along their respective bolts 15, and the tension of the resilient clasps 9 and 12 is increased sufficiently to maintain the garments in position on the hanger.

Fig. 4 shows a modified form of the invention in which an ordinary rigid garment hanger is employed, and said hanger is provided on its upper edge on opposite sides of the supporting hook 21, with resilient clasps 22, which clasps are secured 90 in place by means of screws 23. Passing through suitable perforations in the resilient clasps 22, are bolts 24, and each of said bolts 24 passes through an opening in the garment hanger, said openings being provided 100 on opposite sides of the supporting hook 21. The lower end of each of the bolts 24 is screw-threaded as at 25, and mounted on the screw-threaded end of each of said bolts is a thumb nut 26, which latter is adapted 105 to engage the under edge of the garment

hanger to increase the tension of the resilient clasps 22.

In the form of the invention shown in Fig. 5, the resilient clasps 22' are secured to the under side of the hanger 20. The tension of these clasps is regulated by means of the thumb nut 26' threaded on the bolt 25', the head of which engages the resilient clasps as at 24'. The clasps 22' are secured to the under side of the hanger 20 by means of bolts 23'. It is to be understood that in this form of the invention, two resilient clasps 22 are employed, said clasps being arranged on opposite sides of the supporting hook 21.

In the form of the invention shown in Fig. 4, the operation of the device is identical with that described above, the thumb nuts 26 being movable along the screw-threaded end 25 of the bolts 24 for increasing the tension of the resilient clasps 22.

after the garments have been placed thereunder.

Having thus described the invention, what is claimed as new is:

1. In a garment hanger, a plurality of resilient clasps secured thereto on opposite sides of the supporting hook, and means passing through said resilient clasps and through the garment hanger for regulating the tension of said resilient clasps. 25

2. In a garment hanger, resilient clasps rigidly secured to said garment hanger, bolts passing through said clasps and through the arms of the garment hanger, 35 and having a screw-threaded exterior, and nuts movable longitudinally of said bolts on their screw-threaded exterior for increasing the tension of said resilient garment clasps substantially as described.

FREDERICK L. OWEN.
